US00D856848S

(12) **United States Design Patent** (10) Patent No.: **US D856,848 S**
 Kim et al. (45) Date of Patent: **** Aug. 20, 2019**

(54) **AERIAL VEHICLE**(71) Applicant: **SZ DJI Technology Co., Ltd.**,
Shenzhen (CN)(72) Inventors: **Siyoon Kim**, Shenzhen (CN); **Liang Sun**, Shenzhen (CN)(73) Assignee: **SZ DJI Technology Co., Ltd.**,
Shenzhen (CN)(***) Term: **15 Years**(21) Appl. No.: **29/632,193**(22) Filed: **Jan. 5, 2018**(51) LOC (12) Cl. **12-07**

(52) U.S. Cl.

USPC **D12/16.1**; D12/328(58) **Field of Classification Search**USPC D12/16.1, 319-345, 1; D21/436, 438,
D21/441, 442, 443, 444, 447, 448, 449,

Primary Examiner — Marissa J Cash(74) *Attorney, Agent, or Firm* — Sterne, Kessler,
Goldstein & Fox P.L.L.C.(57) **CLAIM**

The ornamental design for an aerial vehicle, as shown and described.

DESCRIPTION

FIG. 1 is a top front perspective view of an aerial vehicle showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the aerial vehicle that form no part of the claimed design.

1 Claim, 6 Drawing Sheets(56)
